UNITED STATES PATENT OFFICE.

RICHARD TÖMLICH, OF MUNICH, GERMANY.

RESERVOIR-BRUSH.

1,088,801.

Specification of Letters Patent.

Patented Mar. 3, 1914.

Application filed June 12, 1913. Serial No. 773,181.

To all whom it may concern:

Be it known that I, RICHARD TÖMLICH, a subject of the German Emperor, and residing at Munich, Bavaria, German Empire, 5 have invented certain new and useful Improvements in Reservoir-Brushes, of which the following is a specification.

The present invention relates to improvements in brushes of that type in which the 10 stock is provided with a container for a detergent, disinfectant, or other fluid, and is perforated on the face to enable exit of the latter.

In brushes of this class the holes in the 15 face must in general be small, and it is an acknowledged inconvenience that the contents of the reservoir do not sufficiently readily flow out when brushing. To obviate this defect I form the face of the 20 brush with a plurality of hollow, pierced elevations, to the tops of which the bristles are applied. These protuberances communicate with the interior of the reservoir, and in the position of use of the brush they 25 constitute cups adapted to receive the detergent fluid or the like.

When employing a brush of this construction its movements are normally such that at any given moment the fluid, while it fills 30 certain of the cups, leaves one or more thereof empty, and it is manifest that the orifice at the bottom of each vacant cup will form an air-inlet and facilitate flow of liquid from the other cups to the bristles during 35 the operation of brushing.

One embodiment of my invention is illustrated by way of example in the accompanying drawing, in which—

Figure 1 is a side elevation and part vertical section of the new brush; Fig. 2 is an underside view, and Fig. 3 an end view of the same.

The brush shown in the drawing consists of a container *a*, which may be of any suitable material and of any shape agreeable to the hand, and has on its face two open-ended protuberances, or nozzles *a*¹, adapted to receive plugs or stopples *b*. These stopples are perforated at *d* and carry the tufts 45 of bristles *c*, which thus crown the prominences, while the surrounding surface of the

container remains free. The detergent or the like is supplied to the reservoir *a* through the orifice of one of the nozzles *a*¹, whereupon the latter is plugged with its 55 stopple *b*, and the brush is then ready for application. In the operative position of the brush the interior of each of the prominences *a*¹ constitutes a cup adapted to hold the fluid in the reservoir *a*. When brushing, one cup will as a rule fill, while the other one is substantially empty, so that air will find access to the interior of the container *a* through the hole *d* of one plug *b* and thus will facilitate egress of fluid 60 through the orifice *d* of the other plug *b*.

It will be observed that when after use the new brush is laid down in the ordinary manner with the bristles upward, fluid can not leak out, as would be the case were an 70 air-hole to be provided on the back or at the side of the reservoir *a*.

Apart from the advantages secured by the novel manner of providing for the entrance of air, the new brush is especially useful in 75 those cases, *e. g.* for certain toilet purposes, where it is desirable that the bristles shall be located in more or less isolated groups, instead of being evenly distributed over the entire face of the stock.

Although for the sake of simplicity I have illustrated but a single form of brush, possessing only two nozzles, it must be understood that I do not desire to restrict myself to the constructional details depicted, as 80 the improved brush may be of any suitable form and dimensions, and may in particular be provided with any desired number of protuberances, constituting cups of any required depth, as will be clear from the ambit 85 of the claims which form a part of this specification.

Having thus described my invention, I declare that what I claim as new is—

1. In a brush, a reservoir, a plurality of 95 nozzles integrally extending from said reservoir, and axially perforated stopples, furnished with bristles, secured in said nozzles.
2. In a brush, a reservoir provided with a plurality of nozzles, and perforated stopples, furnished with bristles, removably inserted in the orifices of the nozzles. 100

3. In a brush, a reservoir whose bottom wall is internally depressed at a plurality of places, so as to present externally a number of isolated prominences, the top of each of which is removed, and perforated plugs, provided with bristles, fitting in the open tops of the prominences.

In testimony whereof I affix my signature in presence of two witnesses.

RICHARD TÖMLICH.
